UNITED STATES PATENT OFFICE.

OLIVER WILSON CLINE, OF FROHNA, MISSOURI.

SADDLE ADJUSTER AND FASTENER.

SPECIFICATION forming part of Letters Patent No. 289,225, dated November 27, 1883.

Application filed May 29, 1883. (No model.)

To all whom it may concern:

Be it known that I, OLIVER W. CLINE, of Frohna, in the county of Perry and State of Missouri, have invented certain new and useful Improvements in a Saddle Adjuster and Fastener; and I do declare that the following is a full, clear, and exact description of the same, reference being had to the accompanying drawings and letters of reference marked thereon, forming a part of this specification.

This invention relates to improvements in adjusting and fastening saddles or saddle-trees to accommodate them to the back of variously-shaped horses, either large or small, or those that may be larger in the withers or smaller in the flanks, or vice versa; and to this end the invention consists in the construction and arrangement of parts, as will hereinafter be more fully described and specifically claimed.

In the annexed drawings, to which reference is made, and which fully illustrate my invention, Figure 1 represents a side view of my adjuster and fastener when fastened to the saddle-tree and girth with a ring and buckle, and Fig. 2 is a similar view with ring only. Fig. 3 is a front view of the same.

Like letters of reference denote like parts in the several views.

A represents the saddle, and B the saddle-tree, both of which in their construction are of the ordinary or usual form.

C are two short metallic straps, having one end each secured to the front and rear of the saddle-tree, upon each side thereof, their free ends being provided with rings D D, and through which passes and connects with said rings D D one single strap, E, having one end provided with a ring, F. This ring F, attached to the strap E, is intended to be movable between the rings D on the tree-straps C, and will have its position changed as the saddle is to be eased on the withers or loins of the horse by being brought nearer to the one or other of said rings D.

G is the girth, provided at one end with a ring, H, and at the other end having a ring, H', and a buckle, I.

The method of attaching and using my device is as follows: Place the ring F, which is attached to one end of the strap E, opposite the point on the saddle-tree B where the fastening is desired to give support, with the in-

side of the strap facing outward, and proceed with the other end of the strap to the ring D on the front part of the saddle-tree B. Pass 55 the strap E through the ring D from the inside outward. Return it to the ring F on the strap E, and then pass the strap E through the ring F from the outside inward, which gives the strap E the natural turn upward to cause 60 the inside of the strap E to face outward, and proceed with it to the ring D on the back part of the saddle-tree B. Pass the strap E through ring D from the inside outward, and return it to the ring F on the strap E, and pass 65 the strap E through the ring F from the outside inward, and carry it thence upward above the ring F on the strap E, so as to include both the strap E and ring F, and bring it outward over the upper part of the ring F. Then carry 70 strap E down through the ring H on the girth G from the inside outward, and return to ring F, as shown in Fig. 2, and again pass the strap E through the ring F from the outside inward, and carry the strap E downward under the 75 lower part of the ring F, and by drawing the strap E down tightly the adjuster and fastener is completely and securely fastened, and that portion of the strap E extending below the ring F is to be used in fastening the girth 80 to the adjuster and fastener, and the method of attaching the girth to the part of the strap extending below will be indicated by the kind of girth used, though a girth with both a ring and buckle for attachment is best both for 85 strength and convenience. When a buckle is used near the end of the girth, as shown in Fig. 1, after the tie is made the end of the strap E will be brought through the ring H, then back through the ring F, and then buckled 90 to the girth. With similar procedure the stay is to be formed on the opposite side of the saddle-tree B.

When it is necessary to adjust the saddle to any position that may be required, in consequence of the difference in size of the horses upon which the saddle may be placed, it can be readily done in a few moments' time, and with but very little trouble, by simply unloosening the tie or buckle and slipping the 95 ring either forward or backward on the strap E on the sides of the saddle-tree from the point of attachment. It will change the point of support of the saddle-tree to the front or rear 100

of the horse, when the knot or loop is then drawn tightly, and prevents the slipping of the saddle too far forward or backward, which is liable to be the case with the ordinary fasten-
5 ings in use.

My invention does away with the use of breast-girth, cruppers, &c., as by my device the saddle is securely held in its proper position without them.

10 What I claim as new, and desire to secure by Letters Patent, is—

The combination of the saddle-tree B, the tree-straps C C, each provided at its pendent end with a ring, D, the single strap E, having at one end a ring, F, and the girth G, provided at each end with a ring, H, and near one end with a buckle, all substantially as shown and described.

OLIVER WILSON CLINE.
